ATTORNEY

UNITED STATES PATENT OFFICE.

HARRY R. MCFARLAND, OF SEATTLE, WASHINGTON.

CAN-OPENER.

1,261,045.

Specification of Letters Patent.

Patented Apr. 2, 1918.

Application filed November 29, 1916. Serial No. 134,158.

To all whom it may concern:

Be it known that I, HARRY RIVERS MCFARLAND, a citizen of the United States, residing at Seattle, in the county of King and 5 State of Washington, have invented certain new and useful Improvements in Can-Openers, of which the following is a specification.

My invention relates to an improvement in a tool, and particularly to a device adapted for use as a can opener.

An object of the invention is to construct a tool of the character described which includes a body portion having a handle at one end thereof, a movable member slidably 15 mounted on the body member and having a guide portion formed in conjunction therewith and extending substantially at right angles, a cutting knife carried by the body portion and disposed to be in a plane substantially parallel with the plane of the 20 guide portion, and an intermediate element carrying a penetrating center pin and having parts associated therewith and with the body member and the movable member in 25 such a way that as the movable member is adjusted along the body member to vary the disposition of the guide portion thereof with respect to the knife of the body portion, the penetrating center pin will be 30 maintained in a substantially centered position between the guide portion and the knife.

A still further object resides in providing means associated with the intermediate element by which the penetrating center pin is carried and which can be tightened down to clamp the movable member in rigid mounting upon the body member when the desired 35 adjustment of the guide or gage portion 40 with respect to the knife has been accomplished.

Yet another object is to provide an outstanding portion bent from the gage portion of the movable member in such relation 45 that during the cutting operation as just described this outstanding portion will grip and hold with the ice while in yet another adaptation this outstanding portion can be used to pry a seal of the "crown" type from 50 a bottle.

A still further object resides in providing a cutting knife for use in opening square cans and the like and in mounting a cork screw, these parts being so arranged that 55 they may be placed in use when the tool is grasped through the medium of a handle

provided to give a grip in the other uses as described.

With the above and other objects in view, my invention consists in other novel features of construction and combinations of parts which will be hereinafter set forth in connection with the drawings and then more particularly pointed out in the claims.

In the drawings:—

Figure 1 is a view in elevation showing the tool and with certain parts of the structure illustrated in dotted lines.

Fig. 2 is a view in edge elevation.

Fig. 3 is a view similar to Fig. 1 but showing the opposite side of the implement.

Fig. 4 is a transverse sectional view taken on the line 4—4 of Fig. 3.

The handle 1 has a body portion or member 2 extended therefrom and as will be 75 noted, this body member consists of a single piece of sheet or scrap metal which is provided with a longitudinally extending slotted opening 3, the rack teeth being formed at 4 along one of the side edges of the slotted 80 opening 3. The opening 3 might be extended throughout the entire length of blade like body member 2, however, in the present adaptation it is necessary that this slotted opening and the rack tooth formation be 85 provided only throughout the length of the outer portion of the body member, and at the extreme end of the body member the chipping point 5 is provided, the end being severed across diagonally and the saw teeth 90 being provided as shown at 6.

It is preferable that the body portion 1 be of a material which possesses some little stiffness, although this member might be of spring metal, and a movable member 7 is 95 provided at its edges with the overhanging hook like flanges 8 and 9 which are disposed to form a guideway for the reception of the body member 2 and while having a reasonably snug fit therewith yet permits 100 free sliding movement of the one portion with respect to the other. At one end of the movable member 7, the sheet or scrap metal piece from which the same is formed is bent downwardly substantially at right 105 angles to provide a gage portion 10 which is curved laterally to adapt the gage member to be received against and fit upon the cylindrical outer surface of cans such as are generally used for the packing of fruit, vegetables, etc. This gage portion 10 is slotted 110 to permit passage of the body portion 2, and

in its straight extent between the side flanges 8 and 9 has the longitudinally extending slotted opening 11. The movable member 7 has rack teeth formed as shown at 5 12 along one of the side edges thereof and oppositely disposed with respect to the rack teeth 4, although it is to be understood that the teeth of the rack portions 4 and 12 are of the same pitch. The body member 2 has 10 a knife 13 extending at right angles from the lower side thereof adjacent the handle, and this knife which has the width thereof disposed transversely of the body member is made pointed and is sharpened on one or 15 both edges.

By the arrangement of the parts as set forth, when the movable member is shifted along the length of the body member, the space between the gage portion 10 and the 20 knife 13 is varied, and as the gage portion 10 is to fit on and bear against the outer surface of the can adjacent to the head end thereof while the knife is to be penetrated through the head of the can and to be moved 25 in a substantially circular path to cut through the head of the can so that the top cover will be opened, it is necessary that a center be provided around which the parts of the tool can swing and pivot. With this 30 purpose in mind, I provide the penetrating center point 14 which is made in substantially the form of a spur and is provided with a screw threaded shank or stem 15. A substantially rectangular plate 16 is secured in conjunction with the centering point 14 and is made of such size that it can be fitted against the under side of the body portion 2 to rest between the flanges 8 and 9 of the movable member as the stem or 40 shank 15 is fitted through the registering slotted openings of the members 2 and 7, this fitting of the plate holding the centering pin against turning movement. A gear wheel 17 is made of such size that it can be fitted in the slotted openings 3 and 11 and in this relation will mesh with the teeth of the rack portions 4 and 12, this gear being provided with a central opening by which it may be loosely mounted over the stem or 45 shank 15 to be capable of turning movement. A washer 18 is mounted over the stem 15 to bear against the outer side of the movable member 7 and a knob handle 19 is provided with a screw threaded central orifice so that 50 this knob like handle can be placed over the shank or stem to be tightened down against the washer 18 and thus the parts can be clamped in set position. The outer end of the shank or stem 15 is burred or headed 60 over as shown at 20 so that the knob 19 will be held against entire removal from the stem or shank, it however being understood that the stem is not headed over tight down against the knob but that sufficient play is 65 given that the knob may be unscrewed from

the clamping position to thus allow sliding of the rectangular plate 16 and the washer 18. The mounting of the parts as just described disposes these members as a unit which will be referred to as the intermediate portion, and thus the tool consists essentially of the three parts, the body portion, the movable portion and the intermediate portion. 70

By loosening the button 19, the clamping force exerted against the portions 2 and 7 is relieved and then these parts can be freely moved with respect to each other, or by screwing the button 19 down against the washer 18, the washer will contact against the member 7 and the plate 16 will bear against the member 2 to draw these portions together and clamp the same to be rigidly set one with respect to the other in any adjusted position to which they may have previously been formed. As the gear wheel 17 has the teeth thereof in mesh with the teeth of the rack bar portions 4 and 12, the movement of the one member with respect to the other will cause the intermediate portion to 90 be given equalizing movement which will maintain the centering point 14 in the desired relative positioning with respect to the gage portion 10 and the knife 13, and consequently when it is desired to open a can, 95 the button 19 will be turned to release the clamping action of the same and then by placing the gage portion 10 against the outer wall of the can adjacent to the top and through the medium of the handle 1 moving 100 the parts sufficiently that the knife 13 rests upon the top of the can adjacent to the diametrically opposite point to the fitting of the gage portion 10, the point 14 will be centered after which bearing pressure exerted to force the tool downwardly will cause the knife 13 and the point 14 to be penetrated through the top. The gage portion 10 will hold the parts against displacement from the can while the centering portion 14 will give a central pivot around which the tool can be swung through grasping the handle 1 and the swinging movement of the tool will cause the knife 13 to cut the top around the side edge. 110

A cork screw 21 is pivoted by the pin 22 to be capable of movement to fold against the under side of the body member 2 and may also be swung to extend substantially at a right angle therefrom so that a cork screw 120 is presented in a position for most efficient use, and a cutting blade 23 is mounted on the body member 7 at one side and is provided with a pointed end and a cutting edge 24, a bent up lug 25 being so positioned that this 125 knife blade can be used in opening square or other shaped cans in the same manner as the usual form of can opener. When the can opener blade is to be used, the movable portion 7 will be led along the length of the 130

body portion 2 until the end thereof carrying the knife blade 23 is disposed adjacent to or beyond the toothed outer end of this body portion and then the knob 19 is tightened down to clamp the movable portion against backward shifting, in which relation the handle 1 may be grasped and the device may be used with great efficiency as a can opener, the lug 25 being presented to act as 10 a fulcrum in the raising of the handle to cause the knife edge 24 to cut.

When the tool is to be used in cutting or splitting a cake of ice, the saw toothed edge 6 may be moved backwardly and forwardly 15 in the line which the cut or break is to take and this operation can be continued until a proper kerf is obtained after which the splitting of the cake or piece of ice can be accomplished by bringing the chipping or 20 breaking point 5 sharply down within the kerf, or where it is desired to break a cake or piece of ice without first making a kerf or mark, the knob 19 will be unscrewed to loosen the intermediate member and then 25 the movable member 7 is brought down to have the outer end thereof provided with the extension 10, received against the cake or piece of ice after which the body portion 2 is moved back and forth in a reciprocatory 30 path through this movable member 7 and then the repeated blows of the point 5 will all strike in identically the same place thus accomplishing a better breaking action. To maintain the movable member 7 in the 35 proper set position so that it is assured that the point 5 will always strike at the same spot, the extension 26 is cut and bent from the guide extension 10 and is preferably somewhat sharpened at its outer edge so that 40 as this extension 26 is placed against the cake of ice, it will bite into the surface of the same and will hold the movable portion 7 against shifting. When the movable member 7 is brought to the raised relation 45 shown in Fig. 2, this extension 26 can be used in prying off "crown" or other like bottle seals, the body portion 2 being presented to be received against the top of the cap and the extension 26 positioned to grip 50 under the crimped edge of the cap where the same is held below the bead around the bottle neck.

I claim:

1. A tool including a body member; a 55 movable member slidably mounted on the body member, a guide carried by one of said members, a knife carried by the remaining member, an intermediate member provided with a centering point and mounted in con-

junction with said body and movable members to be maintained in a centering position between the guide and knife and to adapt the tool for use as a can opener, and means by which said intermediate member is locked to maintain the body member and the movable member in a fixed position with respect to each other. 60

2. A tool including a body member, a handle carried at one end of said body member and by which the same is held and 70 moved, a movable member slidably mounted on the body member and having a guide carried at one end thereof away from the handle of the body member, a knife carried by the body member adjacent the handle, an 75 intermediate member provided with a centering point mounted in conjunction with said body and movable member to be maintained in a centering position between the guide and knife and to adapt the tool for use as 80 a can opener, said intermediate member having a screw threaded shank formed at the top thereof, and a knob handle fitted on the screw threaded shank to be turned down theretonto and to clamp and rigidly secure 85 the movable member in set adjustment upon the body member.

3. A tool including a body member made of elongated form and provided with a slotted opening having teeth formed along 90 one side thereof to provide a rack, a movable member slidably mounted on said body member provided with a slotted opening corresponding to the opening of the body member and having rack teeth formed at the 95 opposite side thereof, a guide carried by one of said members, a knife carried by the remaining member, an intermediate member having a centering point carried thereby provided with a gear wheel to be received 100 in the slotted openings in mesh with the rack teeth of each of the members, said parts being so mounted that as the two main members are moved with respect to each other to secure the proper adjustment of the guide 105 with respect to the knife the intermediate member will be maintained in a centering position to thus adapt the tool for use as a can opener, and means by which said intermediate member can be locked to maintain 110 the body member and the movable member in fixed position with respect to each other.

In testimony whereof I affix my signature in presence of two witnesses.

HARRY R. McFARLAND.
